OR D 13,904

DESIGN FOR A CURTAIN-BAND.

SPECIFICATION forming part of Design No. 13,904, dated May 15, 1883.

Application filed March 19, 1883. Term of patent 7 years.

UNITED STATES PATENT OFFICE.

JOHN OTIS REMINGTON, OF HINGHAM, ASSIGNOR TO BURR, BROWN & CO.,
OF BOSTON, MASSACHUSETTS.

DESIGN FOR A CURTAIN-BAND.

SPECIFICATION forming part of Design No. 13,904, dated May 15, 1883.

Application filed March 19, 1883. Term of patent 7 years.

To all whom it may concern:

Be it known that I, JOHN OTIS REMINGTON, a citizen of the United States, residing at Hingham, in the county of Plymouth and State 5 of Massachusetts, have invented certain new and useful Improvements in a Design for Curtain-Bands; and I do hereby declare the following to be a full, clear, and exact description of the invention, such as will enable others 10 skilled in the art to which it appertains to make and use the same, reference being had to the accompanying drawing, and to letters or figures of reference marked thereon, which form a part of this specification.

15 This design comprises a band of gimp composed upon one side of narrow bands or cords in double oppositely-disposed rows of scallops intersecting one another, with the two oppositely-disposed rows somewhat separated, and 20 upon the other and front side a narrow braid

or cord laid upon the first in curved zigzag lines and overlapping the space of the double scallop rows, both the scallops and zigzag being condensed together at the ends of the band both longitudinally and laterally of the latter 25 and finished off with a small head or loop.

The remainder of the design consists of a fringe composed of a body portion of netting of the ordinary diagonal mesh secured to the lower edge of the band, and tassels pendent at 30 intervals from the lower edge of such body.

I claim—

The design herein described and illustrated in the accompanying drawing.

In testimony whereof I affix my signature 35 in presence of two witnesses.

JOHN OTIS REMINGTON.

Witnesses:

H. E. LODGE,
F. CURTIS.
